UNITED STATES PATENT OFFICE.

STEWART ROY ILLINGWORTH, OF BRYNFEDWEN, RADYR, WALES, ASSIGNOR TO THE
ILLINGWORTH CARBONIZATION COMPANY, LIMITED, OF MANCHESTER, ENGLAND.

COOLING OF COKE AND IN APPARATUS THEREFOR.

Application filed May 22, 1926, Serial No. 111,046, and in Great Britain November 27, 1924.

This invention relates to the cooling of coke and the drying of coal in which the sensible heat of the coke is employed to drive off the moisture in the coal, and to apparatus employed in such process.

Coke is usually discharged from retorts in the case of low temperature fuels at about 600° C. and in the case of high temperature coke at about 900° C. The coke is usually 10 placed in chambers to cool or is quenched with water and the heat of the coke is thereby wasted. Moreover in the process of carbonization if wet coal is employed the water has to be expelled at the cost of heat units 15 supplied by the heating gases and the steam thus produced has to be condensed in a recovery plant.

One object of this invention is to utilize the sensible heat of the coke to dry coal, 20 particularly small coal and to obviate the oxidation of coke owing to the fact that cooling takes place in an atmosphere of steam and not in the presence of any appreciable quantity of air.

25 A further object of this invention is to prevent loss of coke due to it becoming ignited if exposed to air immediately on issuing from the retort.

According to this invention wet coal is 30 mixed with hot coke whereby the moisture in the coal is expelled, preferably a moisture content of 3% being left in the coal, which moisture content will be regulated in the following manner.

In a blend of coals such as set out in the 35 examples given in my former British specification No. 229,323 a reduction of 10% is allowed for breeze in cutting or breaking up the coal consequently the amount of non-bituminous coal is 10% less than that set out in the above specification.

These quantities are then measured out 40 by measuring hoppers (such as twin hoppers shown in Figure 11 of the accompanying drawings) and it may be assumed that the quantity of moisture in the coal is 10% to which moisture content coal normally drains.

In my British specification No. 235,627 45 curves are given setting out the theoretical proportions in which wet coal of definite moisture content must be mixed with coal which is at a particular temperature in order

that the final mixture may be perfectly dry and cool (assuming the heat transference efficiency equal to 82%), which curves may 55 be used in the present case in view of the fact that the specific heat of coal and coke is practically the same. The amount of water it is necessary to add to the coal is determined by the curves above referred to. 60

Preferably wet non-caking coal is mixed with hot coke and the required amount of caking coal is added.

The accompanying drawings illustrate apparatus made in accordance with this invention. 65

Figure 1 is a side elevation and Figure 2 a plan showing diagrammatically intermittently working apparatus. Figure 3 is a longitudinal section of a continuously working 70 apparatus, and Figure 4 is a part transverse section of the same. Figure 5 is a side view of the cooling wagon and Figure 6 is an end view thereof. Figures 7 and 8 are details of one of the ends of this wagon. 75 Figure 9 shows a modification of the cooling wagon. Figures 10 and 11 show a preferred form of the hoppers which supply the cooling wagon. Figures 12 and 13 are sections at right angles to a larger scale of the 80 coke breaker shown in Figures 3 and 4.

With reference to Figures 1 and 2, 10 are retort hoppers beneath which is a feed hopper 11 mounted on a carriage 110 so that the feed hopper can be put into communication with either of the hoppers 10, and their corresponding retorts 12. Beneath the retorts 12 is a cooling wagon 13 mounted on a carriage 130. The cooling wagon 13 can be moved to receive the discharge from any 90 of the retorts 12 and also beneath a measuring hopper 14 and the discharge pipe 15 from the cistern 150. When the cooling wagon is beneath the measuring hopper 14 it is also above a coke breaker 16, into 95 which the contents of the wagon are discharged at suitable times. Leading from the coke breaker 16 is an elevator 17 which discharges the coke on to a screen 18, large coke falling into a wagon 19 whilst the 100 small material passes into a hopper 20 below the screen 18. Beneath the hopper 20 is a breaker 21 which discharges to an elevator 22 leading to a conveyor 23 which de-

livers the material to the hoppers 10. 24 is a coal truck adapted to deliver into a coal store 25, the coal from which is conveyed by an elevator 26 to a hopper 27 arranged 5 above the measuring hopper 14.

Referring to Figures 5 to 8 the cooling wagon 13 is in the shape of a cylinder mounted on a carriage 130 and adapted to be rotated on this carriage by a hand lever 10 131 turning a shaft 1310 on which is a toothed wheel engaging with a circular rack 133 on the cylinder. 134 is a door for closing the mouth 1340 of the cylinder.

Figures 7 and 8 show more particularly 15 disks 136 pivoted at 1360 and retained in position covering holes 137 by pawls 138.

As shown in Figure 7 the disks cover all the holes except a limited number at the top of the cylinder some of which are allowed to open by reason of their respective pawls 138 falling out of contact under the action of gravity as the cylinder revolves whereby steam is allowed to be discharged through the open holes 137.

25 In some cases (Figure 9) the carriage 130 of the cooling wagon may be fitted with plates 139 which guide the fuel to the coke breaker 16 whilst the drive of the cooling wagon 13 is coupled to the drive of the coke breaker 16 by a chain 160.

Figures 10 and 11 show a preferred form 30 of the hopper 27 and the measuring hopper 14. In this case the hopper 27 is a twin hopper 270, 271, one hopper for caking and the other for non-caking coal, below each 35 of which is a measuring hopper 14. In this case a second elevator corresponding to the elevator 22 is provided. The capacity of the hopper 14 is varied by the hinged plates 140 which are held in position by pins passing through holes in the quadrants 141. The doors 272 of the hoppers 270 and 271 are operated as shown in Figure 10 by bell crank 40 levers 273.

45 When working the apparatus shown in Figures 1 and 2 with the preferred form of feed shown in Figures 10 and 11, non-caking coal or the coal having the smaller resinic content is dropped into the cooling wagon 13 from the measuring hopper 14, water from the cistern being added if necessary and the cooling wagon 13 is then moved beneath one of the retorts 12 from which it receives hot coke. The wagon is then moved 50 back beneath the measuring hopper 14 above the breaker 16 and is revolved say twice. A caking or bituminous coal from the measuring hopper 14 is then run into the wagon 13, which is revolved five or six times to 55 mix and finally cool the contents. Thus the coal having the smaller resinic content is heated and mixed with the other coal the amount of moisture in the final blend being regulated as described above. The contents 60 of the cooling wagon 13 are now delivered 65

to the coke breaker or cutter 16 from which it is delivered to the elevator 17 and discharged on to the screen 18, the large fuel falling into the wagon 19 whilst the small coal and breeze passes into the hopper 20 70 and thence to the disintegrator 21 and is then delivered by the elevator 22 on to the conveyor 23 to the hoppers 10.

The heat supplied by low temperature coke is generally sufficient to dry the corresponding charge of coal when the moisture contained in the coal is near 10%. 75

The temperature at which the discharge of the cooling wagon takes place should not exceed 80° C. 80

Figures 3 and 4 show an apparatus in which the working is continuous. At the bottom of the retorts 12 is a coke breaker more particularly shown in Figures 12 and 13 in which a frame 28 having spaced members 280 is reciprocated by toggle arms 29 and 30 actuated by a handle 31. Below the reciprocating frame 28 is a fixed frame 32 having spaced members 320. The spaced members 280 coincide with the walls of the retorts when the frame is in the position shown in Figure 13 and the members 320 are midway between the members 280. It will be seen that when the frame 28 is in the position shown in Figure 13 the large pieces of coke are supported by the members 320 and these are fractured by the members 280 as the frame 28 is reciprocated. 85 90 95

Referring back to Figures 3 and 4, beneath the coke breaker is a closed chamber 33 in which is a conveyor 34 by which the coke is delivered to a chute 35 and thence to a drier 36 which is rotated by means of a shaft 360 and toothed wheel 361. 37 is a wet coal hopper which delivers coal to a tray 370 100 which is continuously shaken by means of an eccentric 371. 38 is a sieve conveyor upon which the dried fuel is delivered. The larger fuel proceeds along the sieve and is delivered to another conveyor 39 and from thence to a wagon. The smaller coal and breeze is conveyed by a conveyor 40 to a storage bin. It will be seen that the hot coke after being broken to a suitable size is delivered by the conveyor 34 to the chute 35 where it mingles with the wet coal from the hopper 37 and both enter the drier 36 whence it is delivered to the conveyor sieve 38, the large part proceeding to the conveyor 39 and the smaller to the conveyor 40. In some cases, only wet-non-caking coal is delivered to the hopper 37, the caking coal being introduced into the drier 36 at a lower point where the temperature is between 200° 110 and 300° C. 115 120 125

It will be seen that the mixed coals together with the breeze from the retorts and from the breaking or cutting mechanism are passed to the hopper 20, the amount of bituminous coal being so adjusted that the 130

mixture in the hopper 20 has not less than 5% of resinic matter.

What I claim is:—

1. In a process for cooling hot coke from a coking retort, the step of mixing the hot coke immediately after it comes from the retort with wet coal to cool the coke.

2. A process for cooling coke which comprises adding wet fine coal to hot coke, thoroughly mixing the same to cool the coke, and separating all coke of a definite size from the mixture.

3. A process for cooling coke which comprises adding wet fine coal to hot coke, thoroughly mixing the same to cool the coke,

grinding the mixture and separating the coke above a definite size from the mixture.

4. Apparatus for cooling coke as soon as withdrawn from a retort which comprises a mixer adapted to receive said coke, means for delivering wet coal to said mixer, grinding means adapted to receive the mixture from the mixer, and means for receiving the ground mixture from the grinder for separating the coke from the coal and resultant breeze.

In testimony that I claim the foregoing as my invention I have signed my name this 3rd day of May, 1926.

STEWART ROY ILLINGWORTH.
